COMBINED SPRAYER PUMP AND CONTAINER FOR INSECTICIDES

August H. Pinke, Hastings, Minn., assignor to H. D. Hudson Manufacturing Company, Chicago, Ill., a corporation of Minnesota

Filed Feb. 19, 1960, Ser. No. 59,449

Term of patent 14 years

(Cl. D31—3)

FIG. 1 is a top plan view of a combined sprayer pump and container for insecticides, embodying my new design; FIG. 2 is an enlarged side elevation thereof;

FIG. 3 is a side elevation thereof taken from the side opposite that shown in FIG. 2; and

FIG. 4 is an end elevation thereof.

The dominant features of my design reside in the portions of the drawing shown in full lines.

I claim:

The ornamental design for a combined sprayer pump and container for insecticides, substantially as shown and described.
